UNITED STATES PATENT OFFICE.

CECIL F. DAWSON, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

BLANK FOR CONICAL VESSELS.

Application filed February 9, 1924. Serial No. 691,705.

This invention relates to improvements in blanks for forming conical vessels.

The object of the invention is to provide an improved form of blank capable of being readily formed in conical shape and that will result in the provision of an improved construction of conical vessel.

The invention, with other objects and advantages thereof will be understood from the hereinafter contained detail description, when considered in connection with the accompanying drawings, forming part hereof, and illustrating one embodiment of the invention.

15 In the drawings:

Figure 1 is a plan view of a blank constructed in accordance with the present invention.

Fig. 2 is a plan view of the blank, illustrated Figure 1, when folded flat upon itself on a radius bi-secting the arcuately curved edge of the blank.

Fig. 3 is a plan view illustrating the arrangement of the mandrel relative to the blank at the beginning of the forming operation.

Fig. 4 is a similar view illustrating the mandrel and blank at a preliminary stage of the forming operation.

Fig. 5 is a like view showing the form of the blank at a further stage of the forming operation.

Figs. 6 and 7 illustrate advanced stages of the forming operation.

Fig. 8 is a side elevation of a conical vessel constructed from the blank.

Fig. 9 is a part section and side elevation of the completed vessel.

Referring to a detail description of the particular embodiment of the invention illustrated in the drawings, A designates the blank constructed of paper or other thin flexible material suitable for the purpose. The blank A has a curved edge B extending generally in the arc of a circle, and two substantially straight edges C—D and F—D intersecting each other and said curved edge B, the entire blank being wholly defined by said edges. The major portion of the edges C—D and F—D extend in straight lines. The edges C—D and F—D may, as shown, bend slightly inwardly at C—F toward the blank body to merge in curves with the ends of the curved edge B. Said edges C—D, F—D lie to the outer side of the radii ex-

tending to their respective points of intersection with the curved edge B, and extend at substantially equal angles to said radii, the radial center b of the arcuate edge B lying within the body of the blank. The edge C—D near the point of intersection of the lines C—D, F—D has an inward bend d' , and at the point of intersection of the edges C—D, F—D, these edges bend inwardly, joining each other in a curve, the edge C—D and the edge F—D, if the blank is folded upon itself along a radius bi-secting the curved edge B (as illustrated Figure 2 of the drawings), not coinciding throughout but being separated by an area H.

In the particular exemplification of the invention shown in the drawings, the blank A has an application of adhesive or cementitious material over an area bounded by the edge F—D, the dotted line J—K and the edge portions from F to J and D to K.

The blank is adapted to be formed into a conical vessel by a cone shaped mandrel M in the following manner. The mandrel M is placed upon the blank A as illustrated Figure 3 of the drawings, so that the apex m of the mandrel engages the blank at the point b , the center of the curved edge B, and so that the mandrel contacts with the blank along the line b —C, (indicated by dotted line), the radius extending from the radial center b of the curved edge B to the point of intersection of the edge C—D with the curved edge B. The blank at the point C is held fixed to the mandrel, and with the apex m of the mandrel held fixed at the center b , the mandrel is rolled upon the blank, as illustrated Figures 4 to 6 of the drawings. At the preliminary stage of the forming operation, the edge C—D and the adjacent marginal portion of the blank, excepting that portion thereof at the point C which is held fixed to the mandrel, does not lay against the mandrel but extends in spaced relation therewith in a curl, as shown Figure 4 of the drawings. As the forming operation proceeds, that portion of the blank A between the apex m of the mandrel M and the point D of the blank A, is lifted out of the original plane of the blank, and the point D moves about b , as a center, upwardly in the direction of the curved edge B, as illustrated in Figures 6 and 7 of the drawings. During the winding of the blank A about the mandrel M, as the point C ap-

proaches the edge B adjacent F, there has been sufficient bending movement developed along the edge C—D so that a natural fold begins at a point N, as seen in Figure 6, and 5 results in a fold along the line N—b.

With the blank A provided with adhesive or cementitious material over an area F—J—D—K, it is apparent that a portion of the blank A adjacent edge C—D, approximately that bounded by D—N—b comes in contact with the adhesive or cementitious material, resulting in a bond or union of the two surfaces lying generally within the area D—N—b, (see Figure 6 of 10 the drawings), and after the winding operation has proceeded to a point when the surfaces referred to have been secured together, there is still a portion of the blank adjacent to edge F—D namely F—D, N—b 15 bearing bonding material, that is exposed, and which in the continuation of the winding operation, as indicated Figure 6 of the drawings, is brought in contact with, and overlaps and is cemented to the outer surface 20 of the blank A, that has already been formed to the desired conical shape, the vessel, and the sealing and reinforcing of the same being thus completed as illustrated Figures 8 and 9 of the drawings. 25

As will be appreciated, the particular form of blank hereinbefore described, readily lends itself or is peculiarly adapted to be shaped up in the form desired and results in the provision of a conical vessel structure of a very efficient nature. 30

For some purposes it may be desirable to impregnate or coat the material from which the blank is cut, or the blank after being cut, or the conical vessel after being formed 35 from the blank, with a wax or fusible cementitious material which in itself is capable of being used to bind the overlapping layers of the blank in the formed conical vessel together.

While a specific embodiment of the invention is illustrated in the drawings, it will 40

of course be understood that changes and modifications in the particular construction shown, and the carrying out of the invention in other forms, as will appeal to those skilled in the art and falling within the scope of the appended claims, may be practiced without departing from the spirit of the invention. 50

What I claim is:

1. A blank for forming conical vessels, said blank having an arcuately curved edge and two substantially straight edges intersecting each other and said curved edge, the radial center of said curved edge lying within the blank, said substantially straight edges making substantially equal angles with radii to their respective points of intersection with the curved edge, and one of said substantially straight edges having an inward bend near and extending to the point of intersection of said edges, the blank being adapted to be bent to conical form about the radial center of the curved edge thereof as the central point of bending. 55

2. A blank for forming conical vessels, said blank having an arcuately curved edge and two substantially straight edges intersecting each other and said curved edge, the radial center of said curved edge lying within the blank, said substantially straight edges making substantially equal angles with radii to their respective points of intersection with the curved edge, and one of said substantially straight edges having an inward bend near and extending to the point of intersection of said edges, the blank being adapted to be bent to conical form about the radial center of the curved edge thereof as the central point of bending, and said blank having an adhesive substance applied to the marginal edge portion thereof opposite the substantially straight edge portion that has said inward bend. 70

In testimony whereof I hereunto affix my signature.

CECIL F. DAWSON.
